OF SPRINGFIELD, MASSACHUSETTS, A VOLUNTARY ASSOCIATION.

REVOLVER AND CARTRIDGE-CLIP.

1,258,170.

Specification of Letters Patent.

Patented Mar. 5, 1918.

Application filed August 15, 1917. Serial No. 186,318.

To all whom it may concern:

Be it known that I, JOSEPH H. WESSON, a citizen of the United States of America, residing in Springfield, in the county of 5 Hampden and State of Massachusetts, have invented certain new and useful Improvements in Revolvers and Cartridge-Clips, of which the following is a specification.

This invention relates to means for corr- 10 elating the cartridge cylinder of a revolver and the clip or clips holding cartridges loaded into such cylinder.

In order to facilitate the loading of rev- 15 olvers, the practice of providing clips into which the cartridges are previously assem- bled, and which accomplish the simultaneous loading of the cartridges into the re- 20 volver chambers, has been largely adopted. For a six-chambered revolver it is customary 25 to construct the clips to hold three cartridges, so that two cartridge packs of three cartridges each are loaded into the revolver chambers. This accomplishes the desirable quick reloading of the revolver, but is sub- 30 ject to a disadvantage which it is the purpose of the present invention to overcome.

In order that the cartridges may enter the cylinder chambers readily, it is necessary 35 to provide a considerable amount of play or freedom between the cartridge clip and the 40 necks of the cartridges. This play allows the cartridge clip to slip around somewhat when the cartridges are held in the chambers. It is desirable to prevent this loose 45 play of the cartridge clip and hold it in a fixed or definite position with relation to 50 the revolver cylinder.

To this end the present invention provides 55 interfitting provisions on the rear face of the cylinder and on the cartridge clips respec- 60 tively, whereby the clips are held in proper concentric position relatively to the cylinder. The interfitting provisions are prefer- 65 ably formed as recesses in the rear face of the cylinder, and projections from the clips 70 entering these recesses. It is desirable that 75 the clips should be capable of use either side up, so that in loading the clips with car- 80 tridges it shall be unnecessary to present the 85 clips with one side up rather than the other; and to accomplish this the clips are made 90 with projections to both sides, so that which- 95 ever side fits against the cylinder, the pro- 100 jections on that side will be effective to enter 105 the recesses in the cylinder.

The invention will be described with reference to the accompanying drawings, wherein,—

Figure 1 is a side elevation of a fragment of a revolver, showing the cylinder 60 thereof swung out to the open position for reloading. A portion of the cylinder is shown in section taken on the line 1—1 in Fig. 2;

Fig. 2 is a transverse section on the line 65 2—2 in Fig. 1, looking from the rear, showing the cylinder in the same position and loaded with three cartridges held in a clip, the other three chambers being empty;

Fig. 3 is an elevation of one of the clips; 70

Fig. 4 is an edge view thereof;

Fig. 5 is an enlarged section through the clip on the line 5—5 in Fig. 3.

Referring to Figs. 1 and 2, the cylinder A is shown as an ordinary cylinder for a 75 six-chambered revolver, a a being the cartridge chambers. It differs from the ordinary cylinder only in having depressions or recesses b b formed at its rear face in the positions shown in Fig. 2. These recesses 80 can be advantageously formed by milling them out as grooves with curved bottoms.

The cartridge clip B in the form shown 85 consists of a segmental ring of thin metal plate having recesses c c for receiving the grooved necks of the cartridges, the plate being sufficiently resilient to permit the cartridges to be forced or snapped into these recesses, a construction which is now well known. Each clip has projections d d struck 90 up from it and adapted to enter the recesses b b of the cylinder. The projections d d are formed as tongues partly severed from the metal plate, being located relatively to the cartridge recesses c c in the same positions as the depressions b b in the cylinder with respect to the cartridge chambers a a; so that when the cartridges are loaded into the cylinder, the projections d d on the adjoining side of the clip may enter into two 100 of the recesses b b. The projections d d are formed in pairs, best shown in Fig. 5, so that they project to opposite sides of the clip in such manner that those on the front side which fit against the rear face of the 105 cylinder will enter the recesses of the cylinder; while those on the opposite side of the clip simply project rearwardly and have no function. This duplication of the projections d d enables the clips to be loaded 110

either side up, so that it makes no difference which side of the clip comes to the front when the cartridges are loaded into the cylinder chambers.

5. The projections *d* make a sufficiently close fit with the recesses *b* to hold the clips in concentric position with respect to the cylinder and thus prevent their getting out of place or rattling around, which might result from the necessarily loose connection between the cartridge recesses *c c* and the cartridge necks.

Although the drawing shows a six-chambered cylinder and a clip for three cartridges, it is to be understood that the invention is not limited to any particular number of cartridge chambers in the revolver cylinder, or any particular number of cartridges to be carried by the clip. It is also to be understood that any equivalent construction of interfitting projections and recesses formed the one on one part and the other in the other part, so that the cartridge clips are held in proper concentric position by engagement with the cylinder, is within the scope of the invention. Consequently, the details of construction may be modified without departing from the invention.

30. I claim as my invention:—

1. The combination with a revolver cylinder of a cartridge clip, the cylinder and clip being formed with co-acting provisions whereby when the cylinder is loaded the

clip is held definitely located with respect to the cylinder. 5

2. The combination with a revolver cylinder of a cartridge clip, the cylinder and clip being formed with interfitting projections and depressions whereby when the cylinder is loaded the clip is held definitely located with respect to the cylinder. 40

3. The combination with a revolver cylinder of a cartridge clip, the cylinder being formed with depressions and the clip with projections registering with and entering such depressions, whereby to hold the clip in definite relation to the cylinder. 45

4. The combination with a revolver cylinder of a cartridge clip, the cylinder being formed with depressions and the clip being formed with projections on opposite sides, those on either side registering with and adapted to enter the depressions in the cylinder. 50

5. A cartridge clip formed between the cartridge-holding recesses, with projections adapted to co-act with depressions in a revolver cylinder. 55

6. A cartridge clip formed between the cartridge-holding recesses, with projections on opposite sides, those on either side adapted to co-act with depressions in a revolver cylinder. 60

In witness whereof, I have hereunto signed my name. 65

JOSEPH H. WESSON.
